J. E. CARBIS

WINDOW SASH LOCK

Filed Oct. 18, 1924

INVENTOR
James E. Carbis
BY
John W. Freeman
his ATTORNEY

UNITED STATES PATENT OFFICE.

JAMES E. CARBIS, OF LONG ISLAND CITY, NEW YORK.

WINDOW-SASH LOCK.

Application filed October 18, 1924. Serial No. 744,333.

To all whom it may concern:

Be it known that I, JAMES E. CARBIS, a citizen of the United States, residing at Long Island City, county of Queens and State of New York, have invented new and useful Improvements in Window-Sash Locks, of which the following is a full, clear, and exact specification.

My invention relates to locks and refers particularly to locks suitable for use upon windows.

My invention presents a simply constructed, economical and efficient lock for locking windows from slidable movement and which is adaptable for both the upper and the lower window sashes and which can be unlocked by means of a suitable key and which will snap back into locked position when the window is moved into the locking position.

In the accompanying drawings, illustrating one form of the device of my invention, similar parts are designated by similar numerals.

Figure 1 is a view of a window carrying one of my devices upon each of the sashes.

Figure 2 is a cross-section through the line 2—2 of Figure 3.

Figure 3 is a cross-section through the line 3—3 of Figure 2.

The particular form of the device of my invention shown in the accompanying drawings comprises a casing 10 positioned within a corresponding recess 11 of the side frame 35 of a window sash 12 and fixedly positioned therein by screws as 13.

A shaft 14 is journaled in the casing 10. Revoluble upon the shaft 14 is a hub 15, having the extended angular projection 16 to engage the key 17. The hub 15 is extended into the forked member 18, 18, thus forming a shoulder 19. The forked members 18, 18 are connected by a bar 20. The forked member is connected to the side of the casing 10 by the spring 21.

A shaft 22 journaled in the casing 10 carries the fixedly attached pawl 23 having a cam element 24 and a recess stop 25.

Within a recess of the window casement 50 26 is a member 27, retained in position by screws 28, 28 and of such a shape that the pawl member 23 will abut therein when in normal position.

The operation of the device is as follows:—

When the device is in normal, or locked,

position the pawl member 23 is positioned within the frame member 27 and is maintained in that position by the downward movement of the shoulder 19 upon the pawl 23, caused by the spring 21, 21, the connecting bar 20 resting within the recess stop as 21. The window sash 12 is thus locked from upward movement.

When it is desired to raise the sash 12, 65 the key 17 is fitted to the extended member 16 and the revolution of the forked member 18, 18 causes the connecting bar 20 to ride along the edge of the locking member, or pawl, 23 raising it and releasing it from the 70 frame member 27, thus allowing the upward movement of the sash.

The same device may be employed for purposes of locking an upward sash from downward movement, as indicated in Figure 1, in which case the device is placed in reverse position from that described.

It will thus be seen that my device presents an inexpensive and efficient means for locking a window sash from movement within a window frame.

I do not limit myself to the particular size, shape, or arrangement of parts as shown and described, as these are given simply as a means for clearly defining my invention.

What I claim is:—

1. In a lock in combination with a window sash and window frame, a recessed member within the window frame; a casing recessed within a window sash; a revoluble locking bar within the casing, having a cam edge and placeable within the frame member locking the sash from movement; a revoluble forked member within the casing, the 90 forks of which straddle the locking bar and are connected by means of a bar below the locking bar; and a member extending outside of the casing, the revoluble movement of which will remove the locking bar from 95 the frame recess and means for returning the locking bar into locking position.

2. In a lock in combination with a window sash and window frame, a recessed member within the window frame; a casing recessed within a window sash; a revoluble locking bar within the casing, having a cam edge and placeable within the frame member locking the sash from movement; a revoluble forked member within the casing, the 105 forks of which straddle the locking bar and are connected by means of a bar below 110

the locking bar; and a member extending outside of the casing, the revolute movement of which will raise the forked member, carrying therewith the locking bar 5 from frame recess engagement; and means for returning the locking bar into the frame recess when the window sash is in lockable position.

3. In a lock in combination with a window 10 sash and window frame, a recessed member within the window frame; a casing recessed within a window sash; a revolute locking bar within the casing, having a cam edge, stop recess and placeable within the frame 15 recess locking the sash from movement; a revolute forked member within the casing,

the forks of which straddle the locking bar and are connected by means of a bar below the locking bar, the shoulder of the forked member abutting upon the locking member 20 when the latter is in locked position; a key engaging means exterior of the casing, the revolution of which, through the medium of a key, will raise the forked member, the latter revolving the locking member from 25 locking position in the frame, and spring means having a locking tension upon the forked member.

Signed at New York city, in the county of New York and State of New York, this 15th 30 day of October, 1924.

JAMES E. CARBIS.
